ANDREW P. MONTGOMERY, OF KEW GARDENS, NEW YORK, ASSIGNOR TO A. H. GREBE & CO., INC., OF RICHMOND HILL, NEW YORK, A CORPORATION OF NEW YORK

ACOUSTICAL DEVICE

Application filed April 30, 1930. Serial No. 448,772.

My invention relates to the improvement of sound amplifiers or loud speakers and while not limited in its application, is specially adapted for use in electro-dynamic devices which operate to produce sound waves by the interaction of a movable coil carrying a varying electric current and a magnetic field produced by a coil carrying direct current in which there is some fluctuation.

Several constructions suitable for carrying my invention into effect, are illustrated in the accompanying drawings, but I do not wish to be understood as limiting myself to either the exact form or details shown as both may be modified without departing from the spirit and scope of the present invention.

In Fig. 1 of the drawings, there is shown a simplified cross sectional diagram of one form of the above described electro-dynamic device, in which there is also shown incorporated one form of my invention for improving the operation of the same.

In Figs. 2, 3 and 4, I have shown other forms in which my invention may be applied to get somewhat better results than is obtained by the simple form of Fig. 1.

Referring now to the drawings, the magnetic structure of the electro-dynamic device is shown to consist of a core A, fastened centrally within a surrounding hollow cylindrical member B, headed at both ends and provided in one head with an aperture b, through which the core A projects. The relative diameters of the aperture b and the core A, are such as to provide a narrow annular air gap, shown at C. In this air gap there is supported in suitable manner a small coil D, which is so constrained as to be able to move in the air gap axially, while holding its central alignment.

The core A, carries the usual winding E, which fills the hollow cylindrical member to the greater portion of its depth, leaving a space above the winding which is ordinarily filled by a heavy ring or disk of copper, the use of which is objectionable for reasons to be hereinafter explained.

Currents which carry the music or voice to be reproduced are sent through this coil

D, and it moves back and forth axially, due to the interaction of the current and the radial magnetic field in which the coil is lying. A diaphragm of some sort, indicated here as a cone X, carries the coil, and energized by it, serves to radiate sound waves.

The magnetic field in the air gap is set up by the magnetizing action of the coil E, generally made of many turns of wire. The current in this coil E may be of uniform character, such as is delivered by a good battery, in which case the magnetic field in the air gap is uniform in intensity, not varying with time. In many cases, however, the current through coil E, from other sources of power, is of a pulsating character, and in such cases the magnetic field in the air gap C is also pulsating, increasing and decreasing in intensity according to the current through coil E.

Now, the coil D is generally connected to the secondary circuit of a so-called output transformer so designed as to make the impedance of coil D match this circuit which is furnishing the electric power to operate the device. Whether or not this is the case, the coil D forms part of a closed electric circuit, a circuit in which current will flow if an electro-active force is set up in the circuit.

If the magnetic field in the air gap C is of variable intensity, a voltage will be set up in coil D, according to the well known laws of induced electro-motive force. That is, if this magnetic field in the air gap waxes and wanes, say 120 times a second, an alternating voltage of that frequency will be set up in coil D, and this alternating voltage will cause alternating current to flow in the circuit of which coil D is a part.

Now, this alternating current in coil D will cause it to vibrate axially, thus making the diaphragm send off corresponding sound waves. This is the cause of the familiar "hum" prevalent to a greater or less extent in practically all loud speakers of this type furnished with the modern radio receiving set. Even with no signal coming into the speaker from the receiving circuit, the speaker generates a hum, due to the non-uniformity of the current flowing through coil E.

Coil E is generally used as a choke coil in the modern radio receiver as serving to help suppress the ripples of current in the rectified power supply for the plate circuits of the receiver. But while performing this function, the coil does generate fluctuations in the magnetic field in the air gap, and this causes the hum previously mentioned.

One of the principal objects of the present invention is the prevention of this hum in devices of the type shown and similarly operating apparatus. My invention acts to prevent the variation in the magnetic field of the air gap, even though there may be variation in the current flowing through the magnetizing coil E.

Previous attempts to accomplish this result have utilized rings of copper, or other conducting material, surrounding the pole piece A, and placed between the end of coil E and the air gap D. Such attempts have not proven entirely satisfactory in spite of the fact that large amounts of copper or aluminum have been employed, thus considerably increasing the cost of the device. The increased cost is due not only to the amount of the material used in the rings themselves, but to the increased size of the device as a whole, to accommodate the rings.

My invention consists of associating with such rings of conducting material, considerably reduced in thickness, one or more rings, or other conveniently formed pieces, of magnetic material. I have found a remarkable diminution in the hum of the loud speaker with the use of only one such added ring of iron, placed about as shown at G, Fig. 1. In this figure, the associated ring of conducting material is shown at H.

The ring H I term a damping ring, because its effect is to damp out, or diminish, the fluctuations in the magnetic flux of core A, where this comes in proximity to the air gap. In the core A, inside of coil E, there must necessarily be fluctuations in the magnetic flux, if core E is to carry pulsating current and is to act as an effective choke coil. My invention there serves to prevent these fluctuations in magnetic flux from reaching the air gap C.

The fluctuations set up currents in the ring H, Fig. 1, and these currents, to some extent, act to keep the flux in the air gap constant, but my invention greatly increases the effectiveness of their action.

While I do not limit myself in any way by my explanation of the action of my invention, it seems likely that the greatly increased effectiveness of the damping ring H is due to the increase in its reactance, by the action of the closely adjacent magnetic ring G. To effectively damp out the fluctuations in the air gap flux, the currents which are induced in the damping ring H should be 90 degrees in phase, behind the voltage induced in this ring, and the effect of the magnetic

ring G is to help bring about this condition.

Whether or not this is the correct explanation, the fact remains that the effectiveness of a given amount of conducting material in ring H is greatly enhanced by the addition of the magnetic ring G. So great is the effect that a greatly diminished thickness of damping ring, in combination with only one of my magnetic rings, results in a great diminution in hum of the loud speaker.

I have furthermore discovered that if more than one conducting ring H and one magnetic ring G (Fig. 1), are used, the effectiveness of the scheme is further increased. Thus, in Fig. 2, I have shown a magnetic ring G, G, on either side of the conducting ring H. In Fig. 3, I have shown two conducting rings H, H, and two magnetic rings G, G, and in Fig. 4, I have shown a still more laminated structure. My measurements show that as the number of conducting rings, and correspondingly the number of interspersed magnetic rings, is increased, the effectiveness of a given amount of material is correspondingly increased.

Whereas, I do not wish to limit this application of my idea to certain specific materials, I have found it preferable to use either copper or aluminium for the conducting rings and mild steel for the magnetic rings. Neither do I limit myself to the exact proportions of dimensions as shown in my drawings; it may sometimes be advantageous to have the magnetic rings of greater diameter than the conducting rings, and with some designs of magnetic structure, the magnetic rings may be larger or smaller in diameter, compared to the dimensions of the magnetic circuit as a whole than is indicated in my drawings.

Having thus described my invention, what I claim is:

1. In an electro-magnetic sound reproducer employing a magnetizing coil carrying a pulsating magnetizing current, an air gap in which a pulsating magnetic field is developed, means for diminishing the amount of pulsation of said field, said means consisting of a laminated ring placed between the air gap and the magnetizing coil, said laminated ring consisting of alternating laminæ of magnetic material and non-magnetic material of high conductivity.

2. In a loud speaker of the electro-dynamic type, having a magnetic core, a magnetizing coil carrying pulsating current and an air gap carrying a pulsating flux set up by the pulsating magnetizing current, means to diminish the pulsations in air gap flux, said means consisting of a laminated ring placed between the air gap and the magnetizing coil, said laminated ring consisting of alternating laminæ of magnetic material and non-magnetic material of high conductivity.

3. In a loud speaker of the electro-dynamic

- type, having a central core magnetized by an exciting coil carrying pulsating current and an air gap in which a pulsating magnetic field is developed, means to diminish the pulsations in said magnetic field, said means consisting of a laminated ring placed between the air gap and the magnetizing coil, said laminated ring consisting of alternating laminæ of magnetic material and non-magnetic material of high conductivity.
4. In a loud speaker of the electro-dynamic type, having a core magnetized by an exciting coil carrying pulsating current, an air gap around the core in which a pulsating magnetic field is generated, and means to diminish the pulsations in the air gap flux, said means consisting of copper and iron members placed about the core between the exciting coil and the air gap.
5. In a loud speaker of the electro-dynamic type, having a core magnetized by an exciting coil carrying pulsating current, an air gap around the core in which a pulsating magnetic field is generated, and means to diminish the pulsations in the air gap flux, said means consisting of copper and iron rings arranged in alternating relation about the core between the exciting coil and the air gap.
6. In a loud speaker of the electro-dynamic type, having a core magnetized by an exciting coil carrying pulsating current, an air gap around the core in which a pulsating magnetic field is generated, and means to diminish the pulsations in the air gap flux, said means consisting of conducting members and magnetic members arranged in alternating relation around the core between the exciting coil and the air gap.
7. In a loud speaker of the electro-dynamic type, having a core magnetized by an exciting coil carrying pulsating current, an air gap around the core in which a pulsating magnetic field is generated, and means including a magnetic member interposed between the exciting coil and the air gap acting to diminish the pulsations in the air gap flux.

I affix my signature.

ANDREW P. MONTGOMERY.
